NOZZLE

Duncan Horatio Campbell, Etobicoke Borough, Ontario, Canada, assignor to Wilson & Cousins Co. Limited, Brampton, Ontario, Canada

Filed Apr. 16, 1971, Ser. No. 134,917

Term of patent 14 years

Int. Cl. D23—01

U.S. Cl. D23—34

FIG. 1 is a perspective view of a nozzle embodying my new design;

FIG. 2 is an elevational view thereof taken from the side opposite to that shown in FIG. 1; and

FIG. 3 is an exploded view thereof.

The broken line representation of indicia in the figures is for purposes of illustration only.

I claim:

The ornamental design for a nozzle as shown and described.
